DESIGN FOR A TABLET DISPENSER

Louis A. Boylan, Chicago, Ill., assignor to Walgreen Co., Chicago, Ill., a corporation of Illinois

Application May 6, 1940, Serial No. 92,178

Term of patent 14 years

To all whom it may concern:

Be it known that I, Louis A. Boylan, a citizen of the United States and a resident of Chicago, county of Cook, and State of Illinois, have invented a new, original, and ornamental Design for a Tablet Dispenser, of which the following is a specification, reference being had to the accompanying drawing, forming part thereof.

In the drawing:

Figure 2 is a side elevational view thereof; Figure 3 is a side elevational view of the article with the container element illustrated in dotted lines in Figures 1 and 2 omitted; and Figure 4 is a top plan view of Figure 3.

I claim:

The ornamental design for a tablet dispenser, substantially as shown.

LOUIS A. BOYLAN.
